UNITED STATES PATENT OFFICE

GUY RABY, OF TABLE GROVE, ILLINOIS

SIGN SUPPORT

Application filed July 9, 1931. Serial No. 549,736.

This invention relates broadly to supports, and the primary object of this invention is to provide means for supporting a sign and like advertising data in a position easily achieved and at any predetermined place.

A still further object of the invention is to provide a sign support including a plurality of members which may be readily assembled and disassembled.

10 A still further object of the invention is to provide in a support of the character above mentioned, a supporting arm, provided with means whereby the arm may be readily clamped at the desired adjustment on a supporting post, and further to provide such a support having a suspension element, the latter and said arm being provided with cooperative means whereby the suspension element may extend at a suitable angle from the 20 arm for displaying the sign carried thereby.

Other objects and advantages of the invention will be apparent from a study of the following description, taken in connection with the accompanying drawings wherein:

25 Figure 1 is a front elevational view of the support, the sign being shown in broken lines.

Figure 2 is a side elevational view thereof.

Figure 3 is a top plan view thereof.

Figure 4 is a fragmentary detail sectional

30 horizontal view taken substantially on the line 4—4 of Figure 2 and looking downwardly.

Figure 5 is a fragmentary detail sectional view for clearly showing the manner detachably connecting the reflection member with supporting arms.

With reference more in detail to the drawings, it will be seen that 5 designates generally a supporting post adapted to be disposed preferably in a horizontal position and retained therein by any suitable supporting means.

Post 5 in the present instance is in the nature of a T bar and projecting laterally from the post is a supporting arm 6 enlarged at one end, and has each of said enlarged ends bifurcated as at 7. The rib 5a of the supporting post is received in the furcations of the end 7, and the head 5 of the post is clamped between oppositely extending aper-

tured lugs 8 projecting from the arm 6 at the bifurcated end thereof, and a clamping plate 9. Clamping plate 9 at its end is secured to the lug 8 by suitable bolt and nuts 10.

Thus it will be seen that the arm 6 may be secured at the desired vertical adjustment on the post.

To prevent casual displacement or slippage vertically of the arm 6, the head 5b of the post adjacent each longitudinal edge thereof and at the front and rear faces thereof is corrugated or otherwise formed as at 11 to provide suitable gripping surfaces for the lugs 8 and plate 9.

The arm 6 has extending vertically and upwardly therefrom a substantially Y-shaped suspension member designated generally by the reference character 12. The Y-shaped member 12 has the branches or end portions 13 thereof converging as they approach the arm 6, to merge in a common branch or a shank 14, which latter, at its free end is thickened, the thickened portion of the branch or shank 14 in turn merging into a pin having a relatively large upper non-threaded tapered portion 15 and a substantially cylindrical threaded portion 16.

The arm 6 at the free end thereof is provided with an aperture 17, the same having the bore thereof suitably tapered for receiving the tapered portion 15 of the end. A nut 18 is threadedly engaged with the pin for drawing the tapered portion 15 of the end through the aperture 17. Each of the branches 13 and 14 of the suspension member is provided with a slot 19 elongated longitudinally thereof, and the sign, which latter may be in the form of a metallic plate, or other suitable shape designated generally by the reference character 20 is supported from the suspension element through the medium of suitable fastening devices such as bolts and the like passing through the sign and through the slots 19 all of which is shown clearly by broken lines in Figure 1.

From the foregoing it will be seen that I have devised a sign support which may be readily set up, within or without of doors, and which, when not in use, may be readily

collapsed or disassembled and stored without usurping a great deal of space.

Even though I have herein shown and described the preferred embodiment of the invention, it is to be understood that the same is susceptible of further changes, modifications and improvements coming within the scope of the appended claims.

Having thus described my invention, what I claim as new is:

- 10 1. A support for sign plates and the like comprising a post, an arm extending laterally therefrom provided at one end with a clamp whereby to secure the arm at the desired vertically adjusted positions on the post and a 15 Y-shaped suspension member extending angularly of the arm and including a shank having a tapered pin and said arm being provided with an opening having a tapered bore, 20 and said pin fitting in said bore, and means for urging said pin axially of the bore for securing the same therein.
2. A sign support comprising an arm having an aperture, the bore of which is conical, 25 a substantially Y-shaped member for carrying the sign and having one arm thereof provided with a tapered pin fitted within the bore of said aperture, and means for securing the pin wedged in said bore.
- 30 3. In a device of the class described, in combination, a sign support including a member for carrying the sign and having a shank extension merging into a tapered pin, a supporting arm having an aperture 35 through which the pin extends, means for securing the pin within the aperture against casual displacement, and clamping means connected with the arm for securing the latter at the desired adjustment on a support.
- 40 4. In a device of the class described, in combination, a supporting member corrugated on opposite sides thereof, and having a rib projecting laterally from one of said sides, an arm having one end engaging said one 45 side of the support, and at said one end being slotted longitudinally to accommodate said rib, a clamping plate engaging the other corrugated side of the support and securing means connecting said plate with the proximate end of said arm for forcing said end of the arm and plate into clamping position 50 upon said support.

In testimony whereof I affix my signature.
GUY RABY.
